(57) **CLAIM**

The ornamental design for a still picture recorder for a burglar alarm system, as shown and described.

DESCRIPTION

FIG. 1 is a front elevational view of still picture recorder for a burglar alarm system showing my new design;

FIG. 2 is a top plan view thereof;

FIG. 3 is a rear elevational view thereof;

FIG. 4 is a left side elevational view thereof;

FIG. 5 is a right side elevational view thereof;

FIG. 6 is a bottom plan view thereof;

FIG. 7 is a front elevational view with doors opened;

FIG. 8 is an end view along the line VIII—VIII in FIG. 1 with internal mechanisms removed;

FIG. 9 is a right side elevational view with doors opened; and,

FIG. 10 is a top plan view with doors opened.

The broken line shown in all views are to illustrate environment only and form no part of the claimed invention.
